H. A. DOUGLAS

CIRCUIT CONTINUING DEVICE

Filed Jan. 27, 1921

Fig. 1.

Fig. 2.

Inventor:
Harry A. Douglas
By L. L. Cragg Atty.

UNITED STATES PATENT OFFICE.

HARRY A. DOUGLAS, OF BRONSON, MICHIGAN.

CIRCUIT-CONTINUING DEVICE.

Application filed January 27, 1921. Serial No. 440,482.

To all whom it may concern:

Be it known, that I, HARRY A. DOUGLAS, citizen of the United States, residing at Bronson, in the county of Branch and State 5 of Michigan, have invented a certain new and useful Improvement in Circuit-Continuing Devices, of which the following is a full, clear, concise, and exact description.

My invention relates to circuit continuing 10 devices which employ shells that are assembled with contact carriers and other contact carriers separably coupled with said shells and carrying contacts which are engaged by spring pressed contact.

15 My invention has for its object simplification in the construction and assembly of such devices, the preferred embodiment of the invention being illustrated in the accompanying drawing in which Fig. 1 is an axial 20 sectional view of the device and a portion of a reflector with which it is assembled and Fig. 2 is a view, on a larger scale, of a part of the structure as it is illustrated in Fig. 1.

The metallic shell 3 is formed with 25 bayonet channels 4 provided with seats at their innermost ends which receive the bayonet projections upon a plug receivable in said shell.

The shell is formed with an annular recess 30 within its rear end in which the disc or body 11 of insulation is received. The device illustrated is a so-called single pole device, to which the invention is not to be limited. In the case of a single pole device, the insulating disc 11 is provided with 35 a central hole which, in the embodiment of the invention shown, receives the rear end of a metallic sleeve 12. This sleeve is formed with an external circumferential groove at its rear end preferably by means 40 of spaced apart shoulders 13, 14. The central portion of the disc is tightly held within said groove by and between these shoulders whereby the body of insulation is held in fixed relation with said sleeve. A tubular metallic contact member 15 is in 45 sliding engagement with and within the sleeve 12 and carries the electrical contact 10 upon its inner end. A current conducting wire 16 passes through the bore of the tubular contact 50 15 and through the inner closed end of the tubular contact, the contact element 10 being desirably a facing of solder that secures the inner end of the conductor 55 16 in mechanical and electrical relation

with the tubular contact member. The bore of this contact member is desirably enlarged and snugly receives the serving or insulating covering 17 that is disposed about the wire 16. The inner end of the tubular contact member is desirably flared so as to constitute a shoulder that engages the inner end of the coiled spring 18, the outer end of this coiled spring being engaged with the shoulder 13, the spring being held under compression between this shoulder 13 and the inner end of the tubular contact member whereby the spring is enabled to exert inwardly thrusting pressure upon said contact member.

The extent to which the coiled spring 18 70 may inwardly thrust the tubular contact member when the contact carrier 7 is removed, may be limited by the shoulder 19 formed upon the outer end of this contact member.

In the embodiment of the invention shown the coiled spring 18 surrounds both the sleeve 12 and the tubular contact member 15, the contact member 15 being in sliding engagement with and within the sleeve.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. The combination with a shell; of a body of insulation fixed within and to the shell; a sleeve formed with an external circumferential groove in which the body of insulation is held in fixed relation to the sleeve; a tubular contact member within and movable longitudinally of the sleeve and carrying an electrical contact upon its inner end; a coiled spring surrounding and having abutting engagement with said sleeve and engaging the tubular contact member 100 and exerting inwardly thrusting pressure thereon; and a current conducting wire assembled with the tubular contact member and in electrical connection with said electrical contact.

2. The combination with a shell; of a body of insulation fixed within and to the shell; a sleeve in substantially fixed relation with the body of insulation; a tubular contact member within and movable longitu- 110

dinally of the sleeve and carrying an electrical contact upon its inner end; a coiled spring surrounding and having abutting engagement with said sleeve and engaging the 5 tubular contact member and exerting inwardly thrusting pressure thereon and a current conducting wire assembled with the tubular contact member and in electrical connection with said electrical contact.

In witness whereof, I hereunto subscribe my name this 12th day of November A. D., 1920.

HARRY A. DOUGLAS.
